ATTORNEY.

UNITED STATES PATENT OFFICE.

WALTER D. CARRON, OF CHICOPEE FALLS, MASSACHUSETTS.

VALVE TOOL.

Application filed July 3, 1922. Serial No. 572,611.

To all whom it may concern:

Be it known that I, WALTER D. CARRON, a citizen of the United States, residing at Chicopee Falls, in the county of Hampden and State of Massachusetts, have invented certain new and useful Improvements in Valve Tools, of which the following is a specification, reference being had to the accompanying drawing.

10 This invention refers to valves and more particularly to devices for lifting valves working under a spring tension. It has among its objects:—

15 To provide a valve lifter that will do its work effectively, and with relative ease.

To provide such a lifter that its parts will not interfere with the work or function that it is intended for.

20 To provide such a device with a lifting action that will prevent it from slipping.

To provide the lifter with an arrangement that will enable the same to automatically adjust itself to the valve.

25 To have the lifter adaptable for several different types of valves, in the one construction.

And many other objects that will become apparent as the invention is more fully set forth.

30 This invention slips into the parts of the valve, embraces around the spring and valve stem bosses, and so close as to appear to be a part of the construction. The lever arm is then pushed down with one thumb and the valve is not only raised but locked when 35 lifted in position. The parts of the lifter open against the valve boss and leave a large open space in front of the valve stem so that the pin can be taken out or placed in with 40 the fingers of the operator's hand.

The lifter is then taken out by pressing slightly on the lever arm until it puts the cam off center, and allows the pressure of the valve spring to close it.

45 In the drawings which illustrate by way of example an embodiment of this invention:—

Figure 1 represents a valve lifter embodying this invention, in open position.

50 Figure 2 is a view of the lifter in side elevation in closed position.

Figure 3 is a plan of Figure 1.

Figure 4 is a front elevation of the lifter.

55 Figure 5 is a detail of the valve washer chair used in this lifter.

Figure 6 is a detail of the base of the lifter.

Figure 7 is a detail of the lever arm of the lifter.

Figure 8 is a detail of the pivoting pin 60 and also the part that forms an auxiliary base.

Figure 9 is a view of the lifter opened up and raising a convention type of valve.

Figure 10 is a side view of the lifter 65 opened up.

Figure 11 is a sectional view of modified form, which form is characterized by the construction that pins are used instead of legs to guide and keep the lifter chair and 70 base in registry, and also that the auxiliary base is formed as a part of the chair integrally.

Similar reference characters refer to similar parts throughout the drawings. 75

In the construction shown, the character 1 represents the seat of a valve lifter chair which is made to insert under the washer holding a valve spring. The chair has a back 2 preferably semi-circular so as to conform around the spring of the valve and allow the chair seat to go the whole distance under the washer mentioned.

The chair has legs 3 depending from it 80 downwardly and spaced apart as shown in the drawings. These legs offset in from the back and a pair of surfaces 4 are provided.

A pair of cams 5 on a lifting lever 6 engage with the surfaces 4 and raise or lower the entire chair when the lever is operated. 85

The lever has a semi-circular handle as shown that enables the lever to be given a long stroke without interfering with the engine parts until it has completed its travel.

It joins the sides together and causes them 90 to act together as well as form a suitable means for the operator to catch hold of in operating the device. The handle is shown at 7.

A pair of raised pieces 9 are provided on 95 the base piece 10 which consists of a circular piece adapted to rest on the frame of the engine about the valve stem boss. These pieces 9 are adapted to insert between the legs 3 and guide the chair in its travel.

The lifter base is fulcrumed to the lever at 11, 100 and 12 is an auxiliary base used on such valves as may have a smaller travel than the bottom of the base itself provides.

This piece 12 also provides a guide to rest any- 105 110

thing on that should be used in the work.

- The operation of the device is as follows: First the valve lifter is closed into the position shown in Figure 2 and forced between the valve spring washer and the frame of the valve chamber, and around the boss of the valve stem. The lever then is pressed downwardly until it strikes the frame of the engine and there it stays set.
- 10 When the lever is moved downwardly its cam 5 presses against the surface 4 on both sides of the chair, and forces the chair up with the washer and spring. This takes the tension off of the valve stem and the pin 15 of the same can be taken out without any difficulty because unobstructed access can be had to it. In the drawings the pin is shown in black so as to be easily discernible.
- 20 In the modified form the character given to the legs is also given to the substitute pin for the same and similarly for the auxiliary base.

While the drawings show one form of the invention, it is not desired to limit this application for patent to that particular form, otherwise than limited by the prior art, as many other modifications in the construction could be made that would use the 30 same principles and come within the scope of the appended claims.

I claim:

1. A device of the class described comprising a chair for insertion under the 35 greater portion of the valve spring of an

engine, a semi-circular handle attached to the chair and arranged to encompass the valve spring, a plurality of cams having a peaked end portion, said cams, being arranged to engage with the chair for raising and lowering the same, and means for operating the cams whereby the cams will actuate under the chair for raising and lowering the same and for locking in a set position on the peaked portion. 40

2. A device of the class described comprising a plurality of valve-washer-engaging means spaced on the sides of the washer and away from the front thereof, and a ring handle for keeping the means 50 so spaced, said handle being adapted to dispose adjacent the body of the spring and away from the valve stem portion, a base having a ring base adapted to rest on the frame portion of the engine, said base being 55 adaptable or adjustable for a plurality of differently sized valve mechanisms, and a mechanism for raising or lowering the engaging means and guided by the said base, and operating means for the mechanism 60 adapted to actuate spaced away from the washer so as to permit unobstructed access to the valve stem and its pin.

In testimony whereof I hereunto affix my signature in the presence of two witnesses. 65

WALTER D. CARROW.
